United States Patent Office

Des. 203,886
Patented Feb. 22, 1966

203,886

BOTTLE

Jerome Gould, Encino, Calif., assignor to Campbell Soup Company, Camden, N.J., a corporation of New Jersey

Filed May 19, 1964, Ser. No. 80,060

Term of patent 14 years

(Cl. D58—8)

FIG. 1.

FIG. 2.

FIG. 3.

FIG. 1 is a front elevational view of a bottle embodying my new design;

FIG. 2 is a top plan view thereof; and

FIG. 3 is a bottom plan view thereof.

I claim:

The ornamental design for a bottle, substantially as shown.
